(57) **CLAIM**

The ornamental design for a USB charge card reader, as shown and described.

DESCRIPTION

FIG. 1 is a front perspective view of a USB charge card reader, showing my new design in an open configuration; FIG. 2 is a bottom perspective view of FIG. 1; FIG. 3 is a front elevational view of FIG. 1; FIG. 4 is a rear elevational view of FIG. 1; FIG. 5 is a perspective view thereof, illustrated in a closed configuration; FIG. 6 is a left-side elevational view of FIG. 5; FIG. 7 is a right-side elevational view of FIG. 5; FIG. 8 is a top plan view of FIG. 5; FIG. 9 is a bottom plan view of FIG. 5; and, FIG. 10 is a top plan view thereof, illustrated in a wide-open configuration.

The broken lines shown in the drawings represent portions of the USB Charge Card Reader that form no part of the claimed design. The remaining broken lines depict environmental structure that form no part of the claimed design.
